UNITED STATES PATENT OFFICE.

CHARLES J. VAN DEPOELE, OF LYNN, MASSACHUSETTS; C. A. COFFIN AND ALBERT WAHL, ADMINISTRATORS OF SAID VAN DEPOELE, DECEASED, ASSIGNORS TO THE THOMSON-HOUSTON ELECTRIC COMPANY, OF BOSTON, MASSACHUSETTS.

ELECTRIC RAILWAY-MOTOR.

SPECIFICATION forming part of Letters Patent No. 597,156, dated January 11, 1898.

Application filed June 11, 1890. Serial No. 355,019. (No model.)

To all whom it may concern:

Be it known that I, CHARLES J. VAN DEPOELE, a citizen of the United States, residing at Lynn, in the county of Essex and State 5 of Massachusetts, have invented certain new and useful Improvements in Electric Railway-Motors, of which the following is a description, reference being had to the accompanying drawings, and to the letters and figures 10 of reference marked thereon.

My invention relates to improvements in electric railway-motors and to means for controlling their speed and power. Means are also provided for controlling the direction of 15 rotation, but this latter is altogether independent of the circuit and current controlling devices.

The invention comprises a duplex or double circuit motor, or two separate motors having 20 their armatures and field-magnet coils in series and having sectionally-wound field-magnet coils operating upon the principle set forth in my Patent No. 347,902, dated August 24, 1886.

By referring to this patent it will be seen 25 that the field-magnet, in addition to its usual magnetizing-coils, has a series of sectional coils of which more or less are brought into circuit to simultaneously vary the circuit resistance and the power and counter electromotive force of the motor.

According to the present invention I am 30 enabled to connect both motors in series or to connect them in multiple arc, and in either 35 relation to increase or decrease the number of field-magnet coils in circuit with the armature and thereby to control the power and speed of the apparatus through a more extended range.

With the apparatus effecting the series multiple changes in the circuit relation of the 40 motors I also combine means arranged to open the circuit during the time in which the changes are being effected, and to diminish 45 the spark and consequent danger to the contacts I arrange this device to open the circuit at a number of points simultaneously, and I also embody arc-extinguishing means with the circuit-breaker, so that the circuit is

opened without sparking. The operation of 50 the mechanism described is successive in its order—that is to say, with the motors in one combination I first open the circuit at a number of points simultaneously, then shift the motors to a new circuit relation, and then 55 close the circuit and throw the current through them.

In the drawings, Figure 1 is a plan view of a motor-truck provided with motor mechanism embodying the invention. Fig. 2 is an 60 end view thereof. Fig. 3 is a plan view similar to Fig. 1, differing only in the construction of the motor. Fig. 4 is a side elevation, with parts broken away, and illustrates either of the constructions shown in Figs. 1 and 3. 65 Fig. 5 is a side elevation of the circuit-controlling apparatus. Fig. 6 is a plan view of the circuit opening and closing switch. Fig. 7 is a diagrammatic view of the electrical circuits and circuit-changing devices. Fig. 8 is 70 a view in elevation, partly in diagram, showing a duplex reversing-switch. Fig. 9 is a general diagram of circuits grouping into their respective relations the detached parts shown in Figs. 5, 6, 7, and 8. 75

In the drawings, A represents the frame or platform of an electric locomotive or motor-car; but said frame may also be arranged in the form of a car-truck to receive a car-body.

B is the motor seen in Fig. 1, having a duplex field-magnet B' B² and duplex armatures C' C², one for each field-magnet. In reality there are here shown two motors with their armatures on the same shaft, and I so refer to them hereinafter, since the arrangement 85 illustrated in Fig. 3, where both armatures have a single field-magnet structure, is a full equivalent for all the purposes of this invention. Both armatures are mounted upon a single shaft C, which is sustained in suitable 90 bearings D D upon the frame A. The shaft C carries two commutators D' D², each connected with the coils of one of the armatures. A desirable form of gearing is that here shown, comprising driving-pinion d' d² upon the 95 shaft C, said pinions meshing with driving-gears E' E² upon a counter-shaft E, also supported in suitable bearings upon the frame A.

Two pairs of carrying-wheels F G are carried in suitable spring-boxes also connected with the frame A, and power is transmitted to the carrying-wheels through parallel rods H I, 5 connected at their ends to crank-pins h i upon the carrying-wheels and also at their central portions to crank-pins d upon the driving-gears E' E². With this construction the rotation of the armature-shaft will be communicated to the driving-gears and by them through crank-pins d d to the parallel rods and the carrying-wheels. This arrangement is illustrated in Figs. 1, 2, 3, and 4, the only difference in Figs. 2 and 3 being that only a 10 single field-magnet B³ is shown, both the armatures C' C² being then operated by the same field of force. Furthermore, the single field-magnet B³, when that form is employed, will be so wound and connected that the same 15 electrical conditions can be produced as with the form having two separate field-magnets.

The general structure of the switch mechanism is shown in Figs. 5 and 6. Upon a suitable base J is mounted a vertical shaft K, 20 which passes upward through a dial or plate L, which carries the contact-surfaces. The shaft K carries an arm M, provided with three sets of contact-brushes m' m² m³, adapted upon the rotation of the shaft K to engage 25 the contact-surfaces upon the plate L. A suitable hand-crank k is connected with the shaft for imparting rotary movement thereto. The contact devices upon the plate L are divided into four equal sections—that is, where 30 a single arm M is used. It will be understood, however, that the parts might be differently arranged yet still carry out the invention substantially as set forth, and any such modification would be within and covered by my claims.

In order to prevent excessive sparking and consequent wear of the parts upon the passage of the contact-brushes m' from one division of the switch to another, I employ an 45 electromagnetic arc-extinguisher composed of coils m⁴ m⁵, preferably located below the plate L and sustained upon two iron rods m⁶ m⁶, which form part of the support between the base J and plate L. These electromagnetic 50 nets are connected with circuit-conductors bridging the insulating-sections. Pivoted contact-arms M' M² carry at their free extremities contact-brushes to make and break circuit with the terminals of the coils m⁴ m⁵. 55 Near their circuit-breaking points are placed poles m⁸ m⁹, extending from the cores m⁶ m⁷. A disk O is carried upon the shaft K.

The inner ends of the levers M' M² are provided with antifriction-rollers O' O², which 60 normally ride on the periphery of the disk O, with the free ends of the levers in contact with the terminals of coils m⁴ m⁵, closing the main circuit, which extends from said levers to the switch-contacts bridging the insulating-sections, as shown in Fig. 9. The periphery of disk O is notched to correspond 65 with the insulating-sections between the di-

visions of the main contact switch or commutator, so that whenever the lever M is turned to a position where the circuits controlled thereby are opened the rollers O' O² will drop into corresponding notches upon the periphery of the disk O, allowing the reacting-springs to pull the free ends of the levers M' M² away from the terminals of the magnet-coils and opening the circuit. This opening of the circuit will be accompanied by magnetic discharge from the said coils, which will extinguish the arcs which might otherwise be formed. 80

Figs. 7 and 9 show the dial L, with the circuits and connections extending therefrom, including both sectional field-magnet circuits, and showing also the commutators D' D², representing the armatures of the motor or 85

The outer circumference of the dial L is provided with four sets of contacts 1^a 2^a 3^a 4^a 5^a 6^a 7^a, 1^b 2^b 3^b 4^b 5^b 6^b 7^b, 1^c 2^c 3^c 4^c 5^c 6^c 7^c, 1^d 2^d 3^d 4^d 5^d 6^d 7^d, arranged around its circumference and each set separated by insulating-sections Q R S T. 90

The field-magnets, as described in my aforesaid Patent No. 347,902, are provided with main and supplemental coils. The former are indicated as B⁴ B⁴, Fig. 9, while the latter, B' B², are wound or connected in sections corresponding in number with and connected to the terminals of the sets of contacts. Each field-magnet section is connected with corresponding contacts in two separate sets. For example, the sectional coils of the field-magnet B⁴ are divided into six sections, each connected with one of the insulated segments 1^a to 7^a, and the same sections are connected also with the contacts 1^d to 7^d. Similarly the sectional coils of the field-magnets B² are divided into six sections connected with the segments 1^b to 7^b and 1^c to 7^c. 100

Concentric with the plate L are arranged 110 a number of contact-strips n p p' p² n'. The strips n n' are both connected to the negative or return side of the circuit, and the strips p p' p² are connected with or are so arranged that they may be included in circuit with the 115 positive conductor. The negative brush of the commutator D' is connected by conductor 3 with segment 7^a, representing the inner terminal of the field-magnet coils B⁴, the negative brush of the commutator D² being similarly connected by conductor 4 with segment 7^c, representing the inner terminal of the field-magnet coils B². The arm M is provided with metallic extremities, each carrying contact-brushes m' m², electrically connected by 120 those portions of the arm on which each such pair of brushes is carried. Brushes m', at the extremities of arm M, engage the sectional contacts, and brushes m² are in position to engage the strips n n' or p', according 125 to the position of the arm. A third set of brushes m³ is secured to the arm M in position to engage the concentric (inner) strips p p², which strips are electrically connected 130

through the central metallic portion of the arm when engaged by said brushes. Those portions of the arm M between the set of brushes m^2 and the brushes m^3 are separated by insulating material n^2 . The main positive supply-conductor 1 is connected with the positive brush of the commutator D', and said conductor is connected by a branch conductor 5 with the strip p^2 . The main negative conductor 2 is connected to the strip n , and said strip is connected by conductor 6 with the strip n' . The positive brush of the commutator D² is connected by conductor 8 with the strip p' , which is itself electrically connected with the strip p by conductor 9.

When the contact-arm M is upon any two of the insulating-segments Q R S T, no current will flow in any of the circuits, since in these positions the contact-levers M' M² are in their retracted positions with their rollers in notches of the disk O. On moving the arm M to contacts 1^a 1^b both motors are connected in series, including all the sectional field-magnet coils, the circuit being through conductor 1, armature D', conductor 3, segment 7^a, field-magnet coils B' to segment 1^a, thence by arm M to strip p' , thence by conductor 8 through positive brush into commutator D² and its armature, thence by brush N, conductor 4, segment 7^c to and through all the field-magnet coils B², thence to segment 1^b, through the other extremity of arm M to strip n , and thence to return conductor 2. As the arm M is moved toward segments 7^a and 7^b sections of the field-magnet coils are cut out, although all sections remaining are still in series relation.

When it is desired to change the motor system from series to multiple-arc relation, the contact-arm is first moved into position upon the insulating-segments S T, when by further movement the motors will be connected in multiple arc. In the position indicated in dotted lines, Figs. 7 and 9, the current flows through conductor 1 and brush P to commutator D' and its armature, thence by brush N, conductor 3, segment 7^a, such portion of the field-magnet coils B' as may be in circuit between 7^a and 4^a, thence through the outer end of arm M to negative strip n' , thence through negative strip n to the main return conductor 2. Simultaneously the main current will pass from the main conductor 1 by conductor 5 to strip p^2 , thence through the central metallic portion of the arm M to strip p , thence by conductor 9 to strip p' , thence by conductor 8 to brush P of commutator D², thence through brush N and conductor 4 to segment 7^c, thence through such sections of the field-magnet coils B² as may be in circuit with the arm M, (indicated on segment 4^c,) thence through the outer end of the arm M to the return strip n , both motors being thus coupled in multiple-arc relation across the supply-conductors 1 2.

With this construction it will be apparent that by a movement of the arm M upon the

plate L the motors may be connected simultaneously, first, with their armatures and all the sectional field-magnet coils in series, giving the maximum possible resistance, then that sections of the field-magnet coils may be cut out successively until all are out of circuit, when the motor-circuits will both be opened without destructive spark; second, that by continued movement of the arm the motors will be connected up in multiple arc with the field-coils of each machine still in series with its armature, thereby reducing the resistance of the motor-circuits and increasing the power and speed of the motors, after which the sectional field-magnet coils may be cut out successively, diminishing the resistance and increasing the speed until the last sectional coil is cut out, the circuits opened, and the arm M returned to its first position.

The width of the contact-brushes carried by the arm M, as indicated in Figs. 7 and 9, is such that the circuit relations of the motors in whichever direction the arm is traveling are established during the time that the circuit is open at the circuit-breakers M' M².

Obviously the parts heretofore described might be constructed or arranged somewhat differently and without departing from the invention.

In order to control the direction of rotation of the motors, I provide a simple reversing-switch U of any well-known form, comprising two sets of double contacts V W, to which the main conductors are connected. The switch-contacts are controlled by a hand-lever and connection Y and can be thrown for either direction, as desired. Conductors 10, 11, 12, and 13 extend from the fixed terminals of their reversing-switch to the main brushes of the commutators D' D². Conductors 1 3 and 4 8 from the circuit-controller are connected to the reversing-switches, so that the flow of current through said commutators and their armatures is reversed without altering the flow of current through their field-magnets—that is to say, the motors are reversed by a single movement of the lever Y and connected parts, whether connected in multiple are or in series.

Various minor modifications may be made in the herein-described invention by persons skilled in the art without departing from the scope or nature thereof.

Having described my invention, what I claim, and desire to secure by Letters Patent, is—

1. As a means of controlling electric motors, and in combination, a circuit-interrupting device adapted to interrupt the circuit of the current-supply at a number of points simultaneously, and a current-changing device effecting relative changes in the circuits of the translating device during the time that the current is so interrupted, substantially as set out herein.

2. The combination with a plurality of elec-

tric motors, of a switching device adapted to change the circuit relation of the motors, and means for opening the circuit during such changes at a number of circuit-breaking points in series and independent of the points or contacts where the circuit changes are made.

3. The combination of a system of electric motors or motor-circuits with a series of fixed and movable contacts for coupling the motor-circuits in different orders, and thereby regulating the power and speed of the driven mechanism, a separate set of fixed and movable contacts forming a number of circuit-breaking points in series, and a common unitary switch or controller mechanism with which both said series of contacts are so related that by a single handle or moving part the circuit-changing contacts and circuit-breaking contacts will be brought into operation in a predetermined consecutive order.

4. An electric motor having independent field and armature circuits, and means for varying the circuit relation therethrough in any desired order, in combination with a circuit-interrupting device provided with means for simultaneously interrupting the circuit at two or more independent points before each current change is effected and simultaneously restoring the circuit again after such change is effected.

5. An electric motor provided with two or more armature-circuits, two or more field-magnets, and a circuit-changing device for varying the current relations therethrough in any desired order, in combination with a circuit-breaking device provided with means for interrupting the circuit at one or more points before each current change is effected, and for restoring the circuit connections after such change is effected.

6. The described method of effecting current changes to suit the requirements of a translating device which consists in first interrupting the current-supply at a number of independent points, then establishing the circuit changes through the translating device at independent points, and again restoring the current at the points where it is interrupted.

7. The described method of controlling an electric motor having two or more armature-circuits and two or more field-magnets consisting in first interrupting the circuit, then effecting the desired change in the circuit re-

lations of the aforesaid field and armature coils, and again reestablishing the circuit after these changes have been brought about.

8. An apparatus for controlling the application of electrical currents to a translating device, consisting of two sets of movable contacting parts and two sets of fixed contacts, one of which sets is connected to independent circuits for varying the current relation through independent parts of the translating device, and the other carried by and provided with means adapted to suddenly rupture the circuits, whereby the current is first ruptured at several independent points and the circuit changes afterward effected through the translating device, substantially as described.

9. The combination of a system of electric motors comprising a number of armature-circuits, with a series of fixed and movable contacts for connecting the armature-circuits in series or multiple, a separate series of fixed and movable contacts affording a number of circuit-breaking points in series, and a single hand-controller mechanism with which both said series of contacts are so related that the circuit-changing contacts and circuit-breaking contacts are brought into operation in a predetermined consecutive order, and the are incident to rupturing circuit connections largely confined to the series of circuit-breaking contacts.

10. The combination with a plurality of co-acting electric motors, having their field-magnet coils provided with sectional contacts, a switch having a duplex set of exposed contacts, and connections between each field-magnet section and two corresponding contacts upon the switch, a movable contact-arm adapted to be moved upon the switch-terminals to connect with the desired field-magnet sections of the several motors, and extended contact-surfaces insulated from the switch-terminals, also engaging the movable part of the switch, and connections between the line conductors and the extended terminals, and between said extended terminals and the armature-circuits of the motors for connecting the circuits of said motors in series or in multiple arc with each other, as desired.

In testimony whereof I affix my signature in presence of two witnesses.

CHARLES J. VAN DEPOELE.
